UNITED STATES PATENT OFFICE.

DELOSS W. MILLS, OF CARO, MICHIGAN.

CRACKER-CHEST.

SPECIFICATION forming part of Letters Patent No. 250,159, dated November 29, 1881.

Application filed September 7, 1881. (No model.)

To all whom it may concern:

Be it known that I, DELOSS W. MILLS, of Caro, Tuscola county, Michigan, have invented an Improvement in Cracker-Chests, of which 5 the following is a specification.

The nature of this invention relates to certain new and useful improvements in the construction of cases or chests for receiving crackers, and from which they are retailed by the 10 dealer, the object being to preserve the crackers and to prevent their breaking.

The invention consists in the peculiar construction of the chest, all as more fully hereinafter set forth.

15 Figure 1 is a perspective view with one of the side walls broken out. Fig. 2 is a vertical central section.

In the accompanying drawings, which form a part of this specification, A represents a 20 suitable case or box, in one side of which is fitted the drawer B, at or near the bottom, and upon the opposite side of the case is formed a projecting shelf provided with a lid, C, designed to close the opening a, the size of said opening 25 being regulated, as desired, by means of the slide b. Transversely across the box, and at the bottom thereof, is placed the low partition or wall c, from the top of which there extends the grated shelf D, the upper end of which 30 rests upon the inner side of the chest upon the side opposite the discharge-opening a, this grate being set upon an incline, as shown. Upon the opposite side from this grate is secured the

shelf or table E, set at a lesser incline than the grate. F is a suitable cover.

In practice the crackers are dumped into the top of the chest resting upon the grate and shelf, a certain quantity falling through upon the projecting shelf. When it is desired to remove any quantity of crackers they are 40 scooped out through the opening a, the crackers sliding down the grate, which sifts the small particles and deposits them in the drawer below, while the crackers pass on to the discharge.

By the use of this chest I am enabled to handle crackers with the least possible breakage, while at the same time they are kept sweet and free from the danger of molding or becoming musty.

What I claim as my invention is—

1. A cracker-chest provided with an opening, a, and lid C, in combination with the grate D and shelf E, substantially as described.
2. A cracker-chest consisting of the box A, 55 provided with the opening a, grate D, shelf E, and drawer B, substantially as specified.
3. A cracker-chest consisting of the box A, provided with the opening a, grate D, shelf E, drawer B, and slide b, substantially as and for 60 the purposes set forth.

DELOSS W. MILLS.
